UNITED STATES PATENT OFFICE.

JOHN E. WAKEFIELD, OF WORCESTER, MASSACHUSETTS.

FOLDING SEAT.

SPECIFICATION forming part of Letters Patent No. 293,384, dated February 12, 1884.

Application filed June 19, 1883. (No model.)

To all whom it may concern:

Be it known that I, JOHN E. WAKEFIELD, of Worcester, in the State of Massachusetts, have invented an Improvement in Folding Seats, of which the following is a specification.

The object of this invention is to render the seat and back very compact when folded, and to keep it out of the way in passing along between the ranges of seats in public buildings; also, to allow for the removal of the seats and their replacement with facility.

In the drawings, Figure 1 is a vertical section of the seat in a folded condition. Fig. 2 is a similar view, with the seat open for use. Fig. 3 is a front elevation, showing one seat open, the other folded, the frame of the folded seat being in section at the pivots of the seat. Fig. 4 is a sectional view, showing a modification of the supporting frame; and Fig. 5 is a front elevation of the same.

The frames A are to be of cast-iron, wood, or other material, and they may be more or less ornamental. I, however, prefer to make the same as hereinafter described.

At *a a* there are pivot-bearings for the seat-frames B. These seat-frames may be provided with cane, perforated wood, or other material as a surface, and the frame itself may be of wood or metal. It is generally of wood, and the pivot-bearings receive pivots fastened to the seat-frames, as shown at *b b*; but the pivots may be a rod passing through the frames A, upon which the seats swing.

The seats, when in position for use, rest upon the bearings *d d*, extending out from the frames A, as shown in Figs. 4 and 5, and when turned up such seats are vertical or nearly so; or there may be a strip of wood, *d'*, running along and fastened to the front legs, to support the seat when in use, as shown in Figs. 1, 2, and 3.

The backs D are composed of wood or metal frames, with cane, perforated veneers, or other surfaces, and the backs and seats are united by hinges *e e*, which are preferably in the form of L-shaped irons fastened to the seat-frame, with the pivots at the upper ends of the vertical portions, as shown; but any suitable hinge may be employed. In order to prevent the backs falling over, there are arm pieces or links *g*, pivoted one at each side thereof either di-

rectly or to a protecting-loop. Said arm-pieces are preferably made broad upon their upper surfaces to form rests, and the said arm-pieces may be united to fixed upward extensions of the frame A; but it is best to hinge them to the swinging radius-bars *h h*, that are pivoted and allowed a limited extent of motion at the upper ends. Any suitable stops can be provided, but it is usually preferable to pivot these radius-bars at the pivot-bearings of the seat, as shown, and to have the stops below the seats, so as to avoid risk of catching the clothing and injuring the same. The stops (most clearly shown in Fig. 4) are in the form of forks *l* at the lower end of the radius-bars *h*, below the pivot *i*. The forks pass in front of and behind the cross-bar *l*, so as to bear upon the same at either one side or the other and limit the swinging movement of the radius-bars *h*.

When in use, a person sitting upon the seat is supported by the pivots and the rests *d*, and the back is allowed a swinging movement to the extent of the motion of the upper ends of the radius-bars. This is a great convenience in public buildings, because when a person is passing behind an occupied seat the occupant will generally lean forward, and the back of the chair can then be pressed toward such occupant and allow more room for the person passing behind.

When the seat is not occupied, it is folded into a very small compass. The seat folds up at the front edge and the back edge goes down, carrying with it the back, which descends, and the arm pieces or links swing downwardly; hence the back of the seat is moved bodily farther away from the range of seats behind it and brought to lie flat against the seat, and the back, being lowered bodily, allows more room for the clothing of a person passing at either side of it, so that there is as much room as possible given at the passages in front and behind the rows of seats, or between one row of seats and the next.

The frame A at the end of the row of seats may extend up and form an arm, as seen by dotted lines in Fig. 2; but usually this is not desirable. A similar arm-piece may be provided between the seats, if required. It is usually best to have the top parts of the links form the arm-pieces, as shown.

At the bottom of the seat there may be a hat-holder, or a holder for an overcoat or other garment.

It is usually preferable to construct the cross-bar *ll'* in such a manner as to form foot-rests for the persons sitting behind. With this object in view, said cross-bar may be of wood, and sufficiently wide to have openings in it for the feet, as shown in dotted lines in Fig. 1; or there may be upper and lower cross-bars *ll'*, as shown by the full lines.

In public halls the seats often require to be removed, so that the room can be used as a promenade or for balls. Ordinarily, after the 15 feet of the seats have been unscrewed the screw-holes easily become filled with dust, and it is difficult to replace the seats, and the screws pull out easily.

To allow for removal and replacing of the 20 seats with facility, I make use of metal sockets *r*, with screw-threads upon the outsides and upon the insides. These sockets are screwed into holes bored at proper places in the floor, so that the top surfaces of the sockets are 25 flush with the floor. The socket may, however, be secured in any other suitable manner. Into each socket a screw is fitted, that is capable of being screwed down into the socket flush with the floor, and there is a neck or contraction below the head of the screw, into which the slotted fork or split foot-piece *s* is passed. This foot-piece is preferably connected at its 30 upper end by a pivot-screw with the cross-bar *l*, so as to be adjusted laterally by swinging it, if necessary, to cause the fork to set into the neck of the screw; but said slotted foot-piece may be upon any convenient part of the body or frame of the folding seat. The upper surfaces of the slotted foot-pieces are recessed 35 sufficiently to allow the screw-heads to enter into the same when screwed down, and thus firmly hold the seat in position.

To remove the seat it is only necessary to loosen the screws, slide the seat and slotted 40 foot-pieces away from the screw-necks, and screw the screws down flush with the floor, and the parts are in place, ready to be used again when the seats are restored to their position.

50 Where it is desirable to contract the frames *A* to lessen the space occupied by the seats when packed away or when being transported, either one or both of the leg-pieces may be hinged to the central part. I have shown the 55 two sets of legs, *t* and *u*, as hinged at *v* to the central part, *A*, of the frames, so that they can be swung toward each other when the seats are removed from the floor. These frames *A* are made double, as seen in Fig. 1, at the 60 places where the upper ends of the legs *t u* are introduced, so that said legs pass into the

spaces between two parallel portions of the cast frames *A*, and the hinge-bolts *v* pass through the frames and the legs.

If it is desired to cause the two leg-frames 65 to fold at the same time, there may be cog-gears upon the upper ends and two intermediate pinions geared together, so that the legs may be opened or closed simultaneously.

When the leg-frames are not made to fold, 70 the legs *t u* may be cast in one with the end frames, *A*, as seen in Figs. 4 and 5.

I claim as my invention—

1. The combination, with the pivoted seat, 75 of a back, hinges connecting the seat and back, supporting-frames, radius-bars pivoted to the frames, mechanism, substantially as described, to limit the movement of such radius-bars, and links connecting the radius-bars to the back, substantially as set forth.

2. In combination with the supporting-frames, the seat *B*, pivots upon which such seat is swung, a back, *D*, hinges connecting the back and seat, radius-bars *h* upon the seat-pivots, links *g*, connecting the upper ends of 85 the radius-bars with the back, forked lower ends upon the radius-bars, and means, substantially as described, to limit the swinging movement of such radius-bars, substantially as set forth.

3. The metallic seat-frames having projecting rests *d*, in combination with the seat *B*, the pivots upon which the seat is swung, the radius-bars *h*, pivoted upon the frames, mechanism, substantially as described, to limit the movement of the radius-bars, the back *D*, hinges connecting the same to the seat, and links connecting the upper ends of the radius-bars with the back, substantially as set forth.

4. The combination, with movable seats, of 100 the split foot-pieces connected therewith, the socket having external and internal screw-threads, and whereby it may be screwed into the floor, and a screw within the socket to confine the split foot-pieces, substantially as 105 set forth.

5. The combination, with the seat, of a split foot-piece united at the upper end to the frame of the seat, and a metal socket and a screw within the same, for confining the split foot-piece, substantially as set forth.

6. A screw for movable seats, formed of a metal socket fastened into the floor and a screw within such socket, for the purpose and as set forth.

Signed by me this 12th day of June, A. D. 115
1883.

JOHN E. WAKEFIELD.
